UNITED STATES PATENT OFFICE

HERMAN HERRENBRUCK, OF BELLEVILLE, ILLINOIS, ASSIGNOR TO ORBON STOVE CO.,
OF BELLEVILLE, ILLINOIS, A CORPORATION OF DELAWARE

DESIGN FOR A STOVE

Application filed May 13, 1929. Serial No. 31,184. Term of patent 14 years.

To all whom it may concern:

Be it known that I, HERMAN HERRENBRUCK, a citizen of the United States, residing at Belleville, St. Clair County, and State of Illinois, have invented a new, original, and ornamental Design for Stoves, of which the following is a specification, reference being had to the accompanying drawing, forming a part thereof.

The drawing illustrates a perspective view of a stove showing my new design.

The lining for colors indicates contrasting colors.

I claim:

The ornamental design for a stove, substantially as shown and described.

HERMAN HERRENBRUCK.
